UNITED STATES PATENT OFFICE.

DARIEN W. DODSON, OF WILKES-BARRÉ, PENNSYLVANIA.

AIR-ESCAPE FOR RADIATORS.

SPECIFICATION forming part of Letters Patent No. 463,291, dated November 17, 1891.

Application filed December 11, 1890. Serial No. 374,270. (No model.)

To all whom it may concern:

Be it known that I, DARIEN W. DODSON, a citizen of the United States, residing at Wilkes-Barré, in the county of Luzerne and State of Pennsylvania, have invented certain new and useful Improvements in Air-Escapes for Radiators, of which the following is a specification.

This invention of an air-escape, when applied to radiators and other steam apparatus and the valve is opened, permits the air to escape from said apparatus and then automatically shuts the valve by the water or condensation of steam immediately following the outgoing air.

In the drawings accompanying and forming a part of this specification, Figure 1 is a front elevation of an air-escape embodying my improvements. Fig. 2 is a similar view of the same, showing the cover or front plate removed, the valve being open. Fig. 3 is a view similar to the last, but showing the valve closed. Fig. 4 is a vertical longitudinal section through the apparatus. Fig. 5 is a similar horizontal section above the drip-collecting troughs. Fig. 6 is a view of the inner side of the front plate. Figs. 7 and 8 show and illustrate the operation of the device for closing the valve by hand.

Similar characters designate like parts in all the figures.

The object of my improvement is to provide for the escape of air or other non-condensable gases and to close the exit within a brief period of time after water or steam shall follow the outgoing gases. This is done by directing the water (or the fluid of condensation when steam flows out) into a bucket operating to close the valve which was previously opened (by hand or otherwise) to permit the air to escape. The accumulation of water acts by its own weight to overbalance another weight and carries the same past the dead-center, when the weight by falling performs the work of closing the valve, and this it does with a force due to the momentum of the weight, at the same time carrying down the bucket and emptying the same.

The casing of my improved apparatus con-

sists of a hollow chamber, which I make in the form of a hollow cylinder that may comprise the back plate 2, the shell 3, and the front plate 4. The said parts 2 and 3 I prefer to form integral and to attach the front plate by means of screws 5, which pass through holes 6 in said plate 4 and enter the holes 7, Figs. 2 and 3, in the flanges 8 and 9, that are formed on the shell 3. Other plate-fastening devices may, however, be substituted for said screws. The air and steam coming from the radiator enter at 10 through the hole 11 of the valve-body 12, and passing the valve-seat at 13, escape through the opening or port 14 into the interior of the casing. The valve-body 12 is or may be affixed to and in the casing by screws 15. The forward part 16 of said body is fitted to receive the threaded stem 17 of the valve 18. The said valve has a head 19, to which is connected the lever or arm 20, that carries at its upper end the weight 21 and at its lower end the bucket 22. The valve-actuating lever 20 is (or may be) placed in a slot 23, formed in the head 19 and journaled on a small pivot-screw 24, inserted in said head. When the lever is swung, as in Fig. 2, to open the valve, the lever strikes against the stop shoulder or edge 25, and when swung to close the valve, as in Fig. 3, rests against the opposite edge 26. Thus the lever has a greater range of motion than the valve.

For operating the valve by hand to open the same I provide a knob or wheel 28, which has a stem 29 journaled in the front plate and provided with an arm 30, whose bended point 31 engages with said lever 20 when the handle 28 is properly turned, as indicated by the arrow in Fig. 6. A spring 33 serves to retract said arm 30, the movement thereof being limited by the stop 32. By this means the said lever, together with its weight and bucket, is shifted from the position shown in Fig. 3 to that shown in Fig. 2. In this position the bucket stands underneath the spout 34 of the drip-collecting trough 35 and receives the water therefrom. The steam entering the casing is condensed on the walls thereof and the water formed above the said

trough finds its way to the bucket, as set forth.

In order to utilize a part of the surface of the plate 4 for supplying water of condensation, I provide on said plate a trough 36, whose spout 37 delivers onto the main trough 35, as best shown in Fig. 5. In practice the steam-jet should be prevented from impinging on the condensing-surface, since this would 10 keep that surface warmer and retard condensation, for which purpose the guard 38 is provided. At the same time any water coming through the port 14 should be utilized, and hence the guard must permit this to flow 15 down the trough to the bucket. For this purpose the guard is cut away at the bottom and the escaping jet is directed upward. In practice, too, the case is externally surfaced in such a manner, by pointing or otherwise, 20 as to promote radiation of heat, thereby increasing condensation and causing the more prompt action of the apparatus.

In some situations—as, for instance, where the pressure of steam is very low, or where 25 the size of the apparatus is very large relatively to the valve—it is not necessary to use the slack-motion connection for attaching the bucket to the valve-stem; but ordinarily it is desirable to use a small-sized apparatus, especially in dwellings, and to provide for the use 30 of steam of a pressure of several pounds per square inch, and in these cases and generally I find it necessary to employ some connection of the class described, whereby to close 35 the valve by impact, and thus to insure the perfect closure thereof. Accordingly in the best form of my invention now known to me I employ the slack-motion device above described, whereby the valve is closed by 40 impact of the weight 21, as set forth, said weight, after being set by hand, being then started in its falling movement by the water accumulating in the bucket. The outlet from the apparatus is by the pipe or opening 45 39 in the boss or internal projection 40. This arrangement provides a means for retaining some water at 42 within the case. This water radiates heat through the lower wall or part of the shell 3 and serves 50 to promote (as I find by experiment) the condensation of steam within the case. The steam entering the case is slightly superheated by expansion and absorbs water from the reservoir 42, and thus becoming more 55 saturated is more readily and rapidly condensed in the space above the troughs. To still further augment the condensing-power of the casing, I sometimes provide a dome or supplemental chamber 50, connecting by a 60 reduced opening 52 with the principal chamber. By this means there is a less rapid agitation and reheating of the steam within said dome and a corresponding increase of its condensing-power. It being desirable to keep 65 the size of case small, as demanded by the trade, and also to provide the water-retaining

reservoir 42 in the case, the valve is preferably set above the center of the case in about the position shown.

It is sometimes necessary or desirable, when 70 the lever 20 stands as in Fig. 2, to close the valve before the same would close automatically. For this purpose I provide a push-button 44, the stem 45 of which slides in a hole through the front plate 4, (being retract- 75 ed by spring 46,) as will be understood from Figs. 7 and 8. The inner end of said stem has an incline or wedge 47, which, when the stem is pushed inwardly as in Fig. 8, strikes against the lever 20 and drives the same away 80 from its position in Figs. 2 and 7 toward the position in Figs. 3 and 8, the movement started by the wedge being completed by the weight 21.

The operation of my invention will now be 85 understood from the drawings and the preceding description. Ordinarily while the radiator or other apparatus to which the air-escape is attached is in use the valve stands closed, the lever 20 standing as in Fig. 3. It 90 being desired to permit the air to escape, the attendant turns the knob 28, and thereby swings the said lever to its position in Fig. 2. The air then rushes past the said valve and escapes by way of the outlet-pipe 39. When 95 the steam arrives, it fills the interior of the casing and is condensed upon the walls thereof. The water of condensation is some of it collected by the troughs and conveyed thereby into the bucket 22 until the increasing 100 weight of this bucket and water overbalances the weight 21 and swings the lever on its pivot 24 against the stop 26, when the weight turns the valve to close the same.

Having thus described my invention, I 105 claim—

1. In an air-escape, the combination of a casing having an interior steam-condensing surface, a drip-collecting wall or trough, an inlet-valve delivering into the space above 110 said trough, and a weight-actuated valve constructed to be closed by the accumulating water of condensation, all substantially as described.

2. In an air-escape, the combination of a 115 casing, a drip-collecting trough, an inlet-valve delivering into the space above said trough, said valve having a screw-stem, a lever connected by a slack-motion joint to operate said valve, and a weight and water-bucket on said 120 valve-lever, the bucket being adapted when loaded with water to inaugurate the falling movement of said weight, all substantially as described.

3. In an air-escape, the combination of a 125 casing, the inlet-valve, a hand-operated valve-opening device, substantially as described, and a gravity valve-closing device, substantially as described, adapted to be set in motion by the weight of the fluid entering the 130 casing through said valve, all substantially as described.

4. In an air-escape, the combination of a casing, the valve, a gravity valve-closing device substantially as described, the hand-operated valve-opener, and the hand-operated valve-closer, substantially as described.

5. In an air-escape, the combination of the casing, the inlet-valve, the trough 35, and the guard 38, substantially as described.

6. In an air-escape, the combination of the valve, the weighted valve-actuating lever provided with a bucket, and devices, substantially as described, to operate said lever in one direction by hand to open the valve, substantially as described.

15 7. In an air-escape, the combination of the casing having the front plate, trough 35, and trough 36 on said front plate and delivering onto said trough 35, substantially as described.

8. In an air-escape, the combination, with 20 a casing provided with an escape-valve opening thereto, of the valve-actuating bucket, the closed dome rising from said casing and communicating with the interior thereof, and means for delivering the water of condensation from the dome to the bucket, substantially as described.

25 9. In an air-escape, the combination of the valve-stem having the head provided with a

slot to receive the lever 20, and a pivot on which said lever is journaled, the whole constituting a slack-motion valve-closing device, substantially as described.

10. In an air-escape, the combination, with the hollow casing inclosing the valve and provided with a reservoir for retaining water 30 whereby to promote saturation of the steam to be condensed for operating the valve, of the valve and its actuator inclosed in said casing, the actuator having a bucket substantially as described, and means for collecting the water of condensation in said bucket, substantially as described.

11. In an air-escape, the combination of the valve-actuating lever, and the stem 45, constructed substantially as described, to actuate 45 said lever, substantially as described.

12. In an air-escape, the combination, with a casing substantially as described, of the inlet-valve and a weighted bucket-lever slack-mounted on said valve, substantially as described.
